C. E. MASON,
MANIFOLD BRACKET FOR HYDRAULIC HOISTS.
APPLICATION FILED NOV. 3, 1919.

1,345.616.

Patented July 6, 1920.

Attorneys.

UNITED STATES PATENT OFFICE.

CHARLES E. MASON, OF DETROIT, MICHIGAN, ASSIGNOR TO GRANT WALDREF, OF ST. PAUL, MINNESOTA.

MANIFOLD-BRACKET FOR HYDRAULIC HOISTS.

1,345,616.

Specification of Letters Patent.

Patented July 6, 1920.

Application filed November 8, 1919. Serial No. 335,548.

To all whom it may concern:

Be it known that I, CHARLES E. MASON, a citizen of the United States, residing at Detroit, in the county of Wayne and State 5 of Michigan, have invented new and useful Improvements in Manifold-Brackets for Hydraulic Hoists, of which the following is a specification.

This invention relates to improvements in 10 manifold brackets for hydraulic hoists, the primary object being to provide a bracket which will form a combined support for a pump below the hoist, the clutch for transmitting driving power from the main driving 15 shaft of the vehicle to the pump and the actuating device for throwing the clutch into and out of connection with the driving element of the clutch on the shaft and form a connection between the pump and the 20 hoisting cylinder for the impelling liquid. My improved manifold bracket enables the parts mentioned to be arranged and assembled in compact form thereby economizing space, producing greater efficiency and effectiveness 25 in operation of the working parts and unifying the structure as a whole so as to simplify and reduce tendency of the parts getting out of running order. The unification of the parts also reduces cost of production and saves time and material in applying the parts to a motor truck for use. With these and other objects and advantages in view my invention comprises the 30 features of construction and combination 35 of parts hereinafter more particularly described and claimed.

In the accompanying drawing forming part of this specification, Figure 1 is an elevation showing a detail of the lower end of 40 a hydraulic cylinder mounted on its support and to which my invention is shown applied, the drive shaft of the vehicle being shown and appearing as when taken upon the section line 1-1 of Fig. 2; Fig. 2 is a side elevation of the structure illustrated in Fig. 1, the driving member of the clutch being also 45 shown upon the driving shaft of the vehicle; Fig. 3 is a front elevation of my improved manifold bracket stripped of all of 50 the parts which it supports and to which it is connected, and Fig. 4 is a plan of my improved manifold bracket.

In the drawing let A indicate the lower 55 end of a hydraulic hoist cylinder which is commonly employed upon motor trucks for

raising and lowering the truck body into and out of dumping position. The lower end of this cylinder is shown provided with the usual combined cylinder end and base 10 which is supported upon the chassis of the 60 motor truck in the usual manner such as by angle bars 11. B indicates the longitudinal main drive shaft of the vehicle which transmits power from the prime mover to the rear wheels for propelling the vehicle. 65

In operating the hoist, impelling liquid is employed such as oil or other suitable liquid which is forced upwardly into the lower end of the cylinder and projects the piston therein, said impelling liquid being 70 forced by a pump C of gear type or any other suitable construction. This pump has the usual pump casing 12 containing an outlet port 13 through which the impelling liquid is projected and valve mechanism 14 75 connected with an ingress or return duct 15 leading from the upper end of the cylinder above the piston, said valve casing being provided with the usual valve operating shaft 16 which is operated by the crank arm 80 17 and connecting rod 18 leading upwardly to a convenient position for the operator to actuate. The pump also has a main driving shaft 19 for actuating its fluid impelling gears, said drive shaft being shown operated by a sprocket wheel 20 although it may be operated by any suitable actuating device. 85

Power for driving the pump originates in the drive shaft B of the vehicle and is connected with the pump by a clutch D, a driving sprocket 21 in alinement with the sprocket 20 and a chain belt 22 traveling over the sprockets 20 and 21. The clutch has the usual sleeve bearing 24 slidably and freely mounted on shaft B and mounted 90 upon said bearing and feathered thereto is a sleeve 25 which is rotatably held in a split collar 26, said collar being supported and held against rotation through bolt connections 49 by my improved manifold bracket 95 E. The bearing sleeve 24 has driven clutch engagements 36 on one end and is formed with a shifting collar 27 on its opposite end in which shifting shoes 28 are mounted, said shifting shoes being connected to the yoke 100 29 of the clutch actuating shifter. This shifter resembles a bell crank fastened on the shaft 30 which is journaled in the manifold bracket E. The operating member or arm 31 of the bell crank is connected to the 105 110

shifting rod 32 extending upwardly to within easy reach of the operator for throwing the clutch with its driven member into and out of connection with the driving member 33 of the clutch. This driving clutch member is mounted on the shaft B and secured rigidly by the bolts 34 and is provided with clutch engaging driving members 35. The end of the sleeve 25 adjacent to the support 26 carries the driving sprocket 21 and when the sleeve 24 is thrust forwardly by pulling up on the rod 32 the clutch engaging elements engage and transmit power from the shaft B through support 24, sleeve 25, sprocket 21, belt 22 and sprocket 20 to the pump shaft 19.

My improved manifold bracket E consists of a skeleton frame which as illustrated is of rectangular form, the outer frame portion 40 having its upper side secured to the lower surface of the combined cylinder end and support 10 by means of the bolts 41. This rectangular frame has one of its sides 42 formed with a depending plate 43 upon the outer side of which the pump casing 12 is secured by bolts 44 at a suitable distance from the main drive shaft B so that the belt 22 may operate efficiently over the sprockets 20 and 21 and be sufficiently close so that a compact structure is produced. The skeleton frame of the manifold bracket is formed with a duct 45 connected with the port 46 in the combined lower end and support 10 of the cylinder leading upwardly into the cylinder and at its lower end with the port 13 in the side of the pump casing. This duct extends downwardly below the cylinder then turns to one side and again down and out through the side of plate 43. The sides of the frame of the manifold and the duct also extend forwardly to most effectively position the pump casing. The manifold bracket is also formed with a reinforcing wall 50 within its rectangular walls which unite with said rectangular walls and with the duct 45 to reinforce the strength of the entire structure with a minimum amount of material. The lower side 47 of the manifold bracket 50 forms a support for the flanged upper end 48 of the clutch holding element 26 to which it is secured by the bolts 49. Thus the manifold bracket produces a unitary structure with a minimum amount of material for supporting the pump, clutch and clutch actuator below the hoist cylinder in compact form and a connection between the pump and cylinder for the transmission of the compelling liquid, said parts being arranged so that the pump may be driven by the drive shaft of the vehicle and so that the valve mechanism of the pump and clutch shifter

may be manipulated from above the base and end of the cylinder.

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. In combination with a hoist cylinder, a drive shaft disposed below said cylinder, a clutch mounted upon said shaft, a pump arranged at one side of the shaft having operating connection with said clutch and a clutch actuator, a manifold bracket having members arranged to support said pump, clutch and clutch actuator in said position and a duct in said bracket leading downwardly from said cylinder into the side of said pump.

2. In combination with a hoist cylinder having a drive shaft arranged below the cylinder, a pump arranged at one side of said drive shaft, a clutch mounted on said shaft and adapted to be connected with said pump to communicate power from the shaft to the driving member of the pump and a clutch actuator associated with the clutch for moving the clutch into and out of clutch engaging position, a manifold bracket secured to the lower end of said cylinder, said bracket being formed with a depending plate on one side to which said pump is attached and with a duct therein leading from the lower end of said cylinder into said pump for the impelling liquid, said bracket being formed with a forwardly projecting lower end upon which said clutch and clutch actuator are mounted.

3. A manifold bracket for the cylinder and pump of a hydraulic hoist, consisting of a skeleton frame having a forwardly projecting lower end and sides, a depending plate from one of said sides adapted to form a support for the pump and a duct leading downwardly through said frame and laterally through said lower side, adapted to form a communication between the pump and the cylinder of the hoist for impelling liquid.

Signed at Detroit, in the county of Wayne and State of Michigan, this 21st day of October, 1919.

CHARLES E. MASON.
